UNITED STATES PATENT OFFICE.

JAMES GOODWIN, OF EVERETT, MASSACHUSETTS.

METAMORPHOSIC ATTACHMENT TO BEDSTEADS.

SPECIFICATION forming part of Letters Patent No. 269,570, dated December 26, 1882.

Application filed April 25, 1881. (No model.)

To all whom it may concern:

Be it known that I, JAMES GOODWIN, of Everett, in the county of Middlesex and State of Massachusetts, have invented a new and useful Metamorphosic Attachment to Bedsteads, of which the following is a specification.

My invention relates to an attachment to bedsteads for the use of invalids and others, whereby I am enabled to make any desired change in the position of the body of the occupant, and also to change the upper and lower position of the body, either together and at the same time or independently of each other and at different times, and, further, am enabled to raise the body from the bed, whether in a sitting or a recumbent position, remove it from the same and deposit it upon a chair or couch at or near the side of the bed, and again restore the body to the bed, all without subjecting the body to any personal change of position or to any involuntary self-movement.

Referring to drawings, Figure 1 is a perspective view of a bedstead attachment embodying my invention. Fig. 2 is a detail view, enlarged, of the arm-socket and its connections. Fig. 3 is an enlarged view in detail of an arm and rods with their connections for moving the person occupying the bed. Figs. 4, 5, and 6 are enlarged views in detail of parts of the working mechanism. Fig. 7 is a top or plan view of the frame, showing the shafts and their several connections to which the canvas is attached and the mechanism for operating the same. Figs. 8 and 9 are detached views, enlarged, of a portion of the frame, showing the joints.

A represents a bedstead of ordinary construction.

C is a canvas, secured in any suitable manner, so as to be readily detached, to the frame r r. (Shown in Fig. 7.)

B is a standard of iron, resting upon the floor of the apartment and supported by means of a bracket attached to the side rail of the bedstead. The said bracket is made in two parts, D J, as shown more particularly in Fig. 4. The two parts D and J are secured together by means of screws a a on the part J, passing through slots in the part D and fastened by nuts, so as to admit of the bracket being ad-

justed to any width of rail of the bedstead. The brackets extend across the top and bottom of the rail, and are secured in the rear by lugs d d.

To the lugs d d are secured by means of screws the lugs d'' d'', which have eyes or holes, through which passes the bar b, having a stay, d, both to be screwed to the floor for the purpose of steadyng the standard B, and so as to turn or swing freely on the same is a socket, E, having a set-screw, e, to hold it in place, and forming a part of an arm, E', which extends across the width of the bed.

In proper bearings, M M, on the arm E E' are supported rods or shafts G H L. (Shown more distinctly in Fig. 7.)

Upon the shaft G are fixed two spools, I I, which carry the belts o' o', attached to the foot end of the frame r. The shaft G is turned by a crank, 1, and is provided with a ratchet-wheel, N, and pawl i, to hold the rod in place as it winds up the belt.

L is a similar rod or shaft, turned by crank 3, and provided with the spools I I, on which are wound the belts o o for the head part of the frame r. The shaft L is also provided with a suitable pawl and ratchet, as on shaft G.

H is a shaft, constructed in two parts, similar to that described in Patent No. 204,026, granted to me May 21, 1878. The two parts H F are connected by a sliding sleeve, F', applied to the adjacent ends of the two parts. The sleeve F' acts as a clutch, so that when fixed on the adjacent ends of the shaft H F it will turn the worm-gears h h at each end of the said shaft H F. The worm-gears h h mesh with worm-pinions g g, that move a shaft on which are the spools I' I'', that carry the belts o'' o'' o'' o'' when the frame that carries the canvas C is to be elevated. The two parts F H are coupled together by the clutch F' when shaft H is turned by the crank applied at 2. When one side of the canvas only is to be lifted the parts F and H are uncoupled, so that either belts o'' o'' or o'' o'' can be wound up separately.

j j', Figs 1 and 3, represent bars or rods to be inserted in an eye in the frame M above and an eye, m, below, secured to the iron side of the bed-rail A. To the rods j j' are attached slides n, carrying a frame, k—one on

each side—which support a table, *l*, the upper part of the said frame having a slot, as shown in Fig. 6, so that it can be adjusted to any desired inclination. The rods *j j'* are held in place in the eye *s* and frame *M* by set-screws *C'*. Fig. 8 is a side view of one of the rails enlarged, showing the joints for the head and foot parts. Fig. 9 is a top view of the same. The frame is composed of hollow tubes united together, as shown at *M M*, so that the end pieces can be readily removed. The head portion *r r* and the foot portion *r'' r''* are connected to the main portion *r'* by means of knuckle-joints *p p'*. (Shown enlarged in Fig. 8.)

15 The joint is composed of the two parts *u v*, so constructed that the head portion can only be moved upward and the foot portion downward. The joint on one side is provided with the projection *w*, which limits the motion of 20 the connecting-piece.

When it is desired to raise the occupant of the bed and place him upon a chair or lounge at or near the side of the bed, the frame carrying the canvas *C* is raised, so as to clear the 25 foot-board. The arm *E*, together with its fixtures, is then swung around on the standard *B*, and the occupant is let down upon a chair or sofa, when the canvas is detached from the frame, and by the same means the body can 30 again be placed upon the bed.

By elevating the canvas and frame from the bed and then elevating the head and foot portions the canvas may serve as a hammock.

What I claim as my invention is—

1. The combination of the standard *B*, the 35 adjustable bracket *D J*, attached to a bedstead, the socket *E*, and swinging arm *E'*, as and for the purpose specified.

2. The combination of the standard *B*, socket *E*, swinging arm *E'*, the separable shaft *F H*, 40 the worm-gears *h' h*, worm-pinions *g g*, carrying the shaft that bears the spools *I' I'* for winding the belts *o² o²*, as and for the purpose substantially set forth.

3. The combination of the standard *B*, socket *E*, arm *E'*, with the shafts *G* and *L*, the 45 spools *I I*, and belts *o o'* for operating the head and foot portions of the frame *r r' r''*, substantially as set forth.

4. The adjustable bracket *D J*, in combination with the standard *B* and bedstead-frame *A*, as and for the purpose specified. 50

5. The combination of the vertical rods *j j'*, the slides *n n*, and adjustable frames *k k*, eyes *s* in frame *r'*, and the frame *M*, as and for the 55 purpose specified.

6. The combination of the adjustable bracket *J D*, the standard *B*, bedstead-frame *A*, and the rear supporting-rod, *b d*, as and for the purpose set forth.

In testimony whereof I have signed my name to this specification in the presence of two subscribing witnesses.

JAMES GOODWIN.
